(57) **CLAIM**

The ornamental design for a ribbon holder, as shown and described.

DESCRIPTION

FIG. 1 is a top, front, and left side perspective view of a ribbon holder showing my new design;

FIG. 2 is a top, rear, and left side perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof;

FIG. 8 is a bottom plan view thereof; and,

FIG. 9 is an additional top, front, and left side perspective view thereof.

The broken-line disclosure in the views represents either portions of the article or environmental structure forming no part of the claimed design.
